Primary Examiner — T. Chase Nelson*Assistant Examiner* — Eric Goodman(74) *Attorney, Agent, or Firm* — Barnes & Thornburg LLP(57) **CLAIM**

The ornamental design for a drainage channel, as shown and described.

DESCRIPTION

FIG. 1 is an isometric view of a drainage channel according to our invention, from above,

FIG. 2 is an isometric view thereof from below and from the opposite end,

FIG. 3 is a side elevational view thereof,

FIG. 4 is a side elevational view from the side opposite to FIG. 3,

FIG. 5 is a top plan view thereof,

FIG. 6 is a bottom plan view thereof,

FIG. 7 is an end view thereof; and,

FIG. 8 is an end view from the opposite end.

The claimed design is shown broken away to indicate that no particular length of drainage channel forms a part of the claimed design.
